UNITED STATES PATENT OFFICE.

DELBERT W. CUSHMAN, OF FREMONT, OHIO.

AUTOMOBILE RUG.

Application filed October 1, 1921. Serial No. 369,157.

To all whom it may concern:

Be it known that I, DELBERT W. CUSHMAN, a citizen of the United States, residing at Fremont, in the county of Sandusky and State of Ohio, have invented a new and useful Automobile Rug, of which the following is a specification.

This invention relates to a rug for use on the floor of an automobile, one of its objects being to provide a means whereby a draft such as usually flows through each slot in the floor of the machine can be prevented without, however, interfering with the proper actuation of the levers.

Another object is to provide a rug which will prevent dust from sifting through the floor of the car.

A further object is to provide a rug suitably reenforced where subjected to the action of the levers, such reenforcement increasing the efficiency of the rug as a closure for the lever slots.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a plan view of the rug in position on the floor of a vehicle and showing the various control levers extending therethrough.

Figure 2 is an enlarged vertical section through a portion of the rug and showing a lever therein.

Figure 3 is a section on line 3—3, Figure 2.

Referring to the figures by characters of reference 1 designates a rug shaped to fit properly on the floor of a motor vehicle and mounted on the upper surface of the rug in the vicinity of the control levers is a top reenforcing layer 2 of leather, strong rubberized fabric, or the like which is fastened on the rug by suitably located rows of stitches such as shown at 3. Extending

thickness 2 are slits 4 which are located above and longitudinally of the slots 5 through which the various control levers 6 are extended. Small openings 7 can be provided at the ends of each slit and the reinforcing thickness 2 can be fastened to the rug by rows of stitches indicated at 8 which extend around and close to the slits. By reason of the thickness of the rug and the weight added thereto by the reinforcing thickness 2, the walls of the slits will normally contact or close together except at those points where the levers 6 are extended through the slits. At such points the walls of the slits will bow oppositely so as to bridge around the lever as indicated at 9 in Figure 3, these bowed portions inclining upwardly and bearing against the lever as clearly illustrated in Figure 2. Thus all portions of the slits are practically closed by the flaps extending longitudinally thereof and which are formed by the material of the rug and the thickness 2 between the openings 7 and along the sides of the slits. When a lever is moved from one position to another it will exert a wedging action within the slit so that the bowed upturned portions of the walls of the slit will follow the lever while those portions of the walls previously held apart by the lever will close together.

What is claimed is:—

As an article of manufacture a complete rug for covering the floor of a motor vehicle, this rug having a reinforcing layer secured to the upper surface thereof, there being a plurality of slits extending through the rug and the reinforcing layer thereon, said slits terminating in openings providing normally contacting flaps formed by those portions of the rug at the sides of each slit, said flaps being flexible to bridge a movable lever extending through the slits and to contact in the path of the lever, the reinforcing layer constituting means for stiffening the flaps and maintaining them normally in closed or contacting positions.

In testimony that I claim the foregoing as my own, I have hereto affixed my signature in the presence of two witnesses.

DELBERT W. CUSHMAN.
